[57] CLAIM

The ornamental design for a novelty cap, as shown and described.

DESCRIPTION

FIG. 1 is a perspective view of a novelty cap showing my new design;

FIG. 2 is a top plan view of a novelty cap showing my new design;

FIG. 3 is a front elevational view thereof;

FIG. 4 is a right side elevational view with the left side being a mirror image thereof;

FIG. 5 is a rear elevational view thereof;

FIG. 6 is a bottom plan view thereof; and,

FIG. 7 is an environmental perspective view thereof.

The broken line showing of the car in FIG. 7 is for illustrative purposes only and forms no part of the claimed design.
